POWER-DRIVEN RECIPROCATING CUTTER

Authnal L. Candland, Vista, Calif.

Application May 8, 1945, Serial No. 592,633

6 Claims. (Cl. 30—272)

1

This invention relates to a power-driven reciprocating cutter, and more particularly to such a device adapted for the use of butchers or similar individuals engaged in the cutting of meat.

A primary object of this invention is the provision of an improved cutting blade, one edge of which has saw teeth, flexibly mounted and adapted to be driven by a flexible cable to impart a reciprocatory motion to the blade for severing cuts of meat, and sawing through the bone thereof.

An additional object of the invention is the provision of such a device wherein the actual cutting implement approximates in size and configuration a conventional butcher knife, and which may be readily handled and operated by either right or left handed persons.

Still another object of the invention is the provision of such a device connected to a motor adapted to be removably supported on a frame, whereby the saw and its associated motor may be readily carried from place to place as desired.

Still another object of the invention is the provision of such a device characterized by means whereby the blade may be readily and quickly replaced as may be necessary.

A still further object is the provision of such a device which will be sturdy and durable in construction, reliable and efficient in operation, and relatively simple and inexpensive to manufacture, assemble and operate.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a side elevational view of one form of device embodying the instant invention showing the motor and support for the same in association with a butcher's block.

Figure 2 is an enlarged fragmentary detail view, certain parts thereof being broken away, disclosing the connection of the motor mechanism with the flexible drive shaft.

Figure 3 is a top plan view of the saw mechanism, certain concealed portions thereof being indicated in dotted lines.

Figure 4 is an end elevational view of the mechanism disclosed in Figure 3, as viewed from the left, the connection to the flexible shaft being omitted.

Figure 5 is a sectional view taken substantially along the line 5—5 of Figure 3, as viewed in the direction indicated by the arrows.

2

Figure 6 is a sectional view taken substantially along the line 6—6 of Figure 5.

Figure 7 is an end view of the construction disclosed in Figure 2, the cover plate being removed, and certain portions thereof being indicated in section.

Figure 8 is an enlarged plan view of a constructional detail.

Similar reference characters refer to similar parts throughout the several views of the drawings.

Having now particular reference to Figure 1, there is generally indicated at 10 a butcher's block of any desired conventional type to which is secured, as by means of clips 11, an upright 12, terminating in an arm 13 extending over the block and provided at its extremity with a hook 14. The hook 14 is adapted to support an electric motor housing 15, encasing an electric motor of any desired conventional type. An electric cord 16 leads from the motor housing 15 through the interior of the support 12 and terminates in a plug 17 which may be plugged into any desired source of current.

25 The motor housing 15 terminates in an enlarged portion 18 having a recess 19 therein adapted to be closed by a face plate 20. The drive shaft 21 of the electric motor extends into the recess 19 and has mounted thereon a member 22 including an eccentrically set pin 23 and a counterweight 24. A set screw 25 (see Figs. 2 and 7) serves to hold the member 22 on the shaft 21. The pin 23 has pivotally mounted thereon a link 26, the opposite end of which is pivotally secured, as by a pivot 27 to an extremity 28 of a flexible shaft 29 which extends through a flexible conduit 30 to the handle, generally indicated at 31, of the power-driven saw mechanism. The lower portion of the extending portion 18 is provided with a threaded nipple 32 to which the conduit 30 is adapted to be secured, as by means of a threaded collar 33. An electric cord 34 extends from the motor housing 15 to the handle 31 and may be secured to the conduit housing 30, as by means of clips 35.

From the foregoing, it will now be seen that when the motor is energized in a manner to be described hereinafter, rotation of the drive shaft 21 is translated through the eccentric member 22 to reciprocatory motion of the extremity 28 of the flexible shaft 29, and hence to the shaft.

Referring now particularly to the handle 31, it will be seen that the same is of substantially the configuration of a normal knife handle and terminates at one extremity in a threaded

55

pie 36 adapted to threadedly engage a collar 37 secured, as by a flange 38, to the extremity of the flexible conduit 39. The flexible shaft 29 extends through a suitable bore 39 into a recess 40 in the interior of the handle 31, and is secured, as by suitable threading or the like, to a rigid member 41 bifurcated, as at 42 (see Fig. 8), and pivotally secured to a reciprocating block 43 provided with rollers 44 which engage in suitable channels 45 formed within the recess 40. The block 43 has pivotally mounted thereon, as by a pivot 46, an elongated member 47 adapted to be passed through a corresponding elongated slot 48 in the extremity 49 of a blade generally indicated at 50. Thus, it will be seen that reciprocation of the flexible shaft 29 is in turn imparted to the blade 50. The blade 50 is provided on one surface with a saw edge 51, the teeth of which are inclined toward the handle 31 in such manner as to impart a drag action when the blade is reciprocated. The opposite edge of blade 50 is provided with a knife edge 52 which terminates in an arcuate extremity 53 to provide a close cutting surface adjacent the blade 51. As best shown in Figure 3, one side of the aperture 40 is closed as by a removable plate 54 pivotally mounted, as at 55, on the handle 31 in such manner that ready access may be had to the member 47 to permit replacement of the blade 50 as may be necessary or desirable.

The electrical connection 34 terminates in a switch mechanism 56 of any desired conventional construction, which is engaged, as by a lever 57, with a conventional switch button 58 of any desired type, whereby the motor may be cut on or off from a convenient point to reciprocate the blade 50 when desired.

From the foregoing, it will now be seen that there is herein provided an improved power saw adapted particularly for butchers' use, wherein the saw blade may be reciprocated to sever the bones of the meat, and wherein the blade may be reciprocated if desired to sever the meat, which may be readily supported adjacent the butcher's block, and which, with its associated motor housing, may be readily removed therefrom when it is desired to cut or carve meat at a location remote from the butcher's block, as for example, within the refrigerator.

It will also be seen that the device hereinbefore shown and described accomplishes all the objects of this invention and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A power driven cutting tool including a hollow handle of square cross section, upper and lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle and pivotal means connecting said cable to said block.

2. A power driven cutting tool including a hollow handle of square cross section, upper and

lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle and pivotal means connecting said cable to said block, the side of said handle adjacent said blade being pivoted to said handle at one end thereof, to form a closure member for the interior of said handle.

3. A power driven cutting tool including a hollow handle of square cross section, upper and lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle and pivotal means connecting said cable to said block, the side of said handle adjacent said blade being pivoted to said handle at one end thereof, to form a closure member for the interior of said handle, said blade being secured to a slide of the block, said side of the block being adjacent to said closure member.

4. A power driven cutting tool including a hollow handle of square cross section, upper and lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle, pivotal means connecting said cable to said block, said block comprising a plate, said plate having its upper and lower edges received in said guide channels, and rollers on said edges bearing in said channels.

5. A power driven cutting tool including a hollow handle of square cross section, upper and lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle, and pivotal means connecting said cable to said block, said pivotal means including a member attached to said cable at one end, the other end of said member bifurcated, said block being pivoted in said bifurcation.

6. A power driven cutting tool including a hollow handle of square cross section, upper and lower guide channels in said handle disposed to one side of the vertical, longitudinal median plane of said handle, a block slidably supported in said guide channels, a cutting blade, means detachably securing said blade to one side of said block, said handle having a slot at one end thereof, said blade being reciprocable through said slot, a flexible reciprocable cable extending into the other end of said handle, and pivotal means connecting said cable to said block, said pivotal means including a member attached to said cable at one end, the other end of said mem-

ber being bifurcated, said block being pivoted in said bifurcation, said other end of said member being enlarged laterally, said bifurcation being offset from the longitudinal axis of said member whereby said block, blade and slot may be 5 positioned closely adjacent one side of said handle.
